MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,378,915.

Specification of Letters Patent.

Patented May 24, 1921.

Application filed March 4, 1920. Serial No. 363,176.

To all whom it may concern:

Be it known that I, MELVIN L. STONE, a citizen of the United States, residing at Lawrence, in the county of Essex and State 5 of Massachusetts, have invented an Improvement in Feeler Mechanisms for Looms, of which the following description, in connection with the accompanying drawings, is a specification, like characters on the drawings representing like parts.

This invention relates to feeler mechanisms for looms whereby filling is replenished prior to complete exhaustion of the filling in the running shuttle.

15 Various types of feeler mechanisms have heretofore been proposed, and in some cases special bobbins have been required in order to coöperate with the feeler mechanisms. In some mills where bobbins having a conical or stepped base portion are used, it has sometimes been necessary to discard these bobbins when adapting a feeler mechanism to the looms, because the feeler mechanism itself has not been of a character lending 20 itself to use in connection with the stepped form of bobbin.

An important feature of the present invention, therefore, consists of the feeler mechanism constructed for use in connection 30 with bobbins having a stepped base portion. By "stepped base portion" is herein meant a series of rings gradually diminishing in size from the head or base of the bobbin toward the tip thereof, the gradations in size being 35 in substantial accordance with the conical wind of the filling when placed upon the bobbin.

The feeler mechanism of the present invention comprises a plurality of feelers each 40 individually capable of operating upon a common actuator to place it in inoperative position when a working supply of filling is present in the shuttle, and permitting it to remain in operative position when filling is 45 substantially exhausted and replenishment is desired. In carrying this feature of the invention into practical effect, a feeler carrier is employed which is mounted for movement toward and from the front of the loom, 50 and its rear end portion is provided with a series of steps or is "stepped," so that the several steps may coöperate with the stepped base portion of the bobbin when filling is substantially exhausted. Associated with 55 the feeler carrier are a plurality of feelers,

one feeler being associated with each stepped portion of the feeler carrier and projecting rearwardly beyond the same, the construction being such that when any one of the feelers is pushed forwardly on a detecting 60 beat, it will operate upon the actuator and place it in an inoperative position so that filling will not be replenished; but when all of the feelers are allowed to remain projected in their normal rearward position 65 relative to the stepped portion of the feeler carrier on a detecting beat, at which time filling is substantially exhausted, the actuator will be permitted to operate and effect replenishment of filling.

70 Other features and novel elements and combination of parts will hereinafter be described in connection with the accompanying drawings, which illustrate a good, practical form of the present invention.

75 In the drawings:

Figure 1 is a perspective view of the feeler side of the loom, some of the parts being broken away and others omitted for clearness of illustration;

80 Fig. 2 is a longitudinal section through the feeler mechanism, showing the action of parts when filling is substantially exhausted on a detecting beat, and all of the feelers, therefore, remain in rearward projected 85 position;

Fig. 3 is an enlarged plan view partly in section, showing the action of the feeler mechanism when a working supply of filling is present in the shuttle; and

90 Fig. 4 is an enlarged detail in plan, showing the several feelers in their fully rearward projected position on a detecting beat, when filling is substantially exhausted and the stepped portion of the bobbin engages 95 the corresponding stepped portions of the feeler carrier.

The loom frame 1 has mounted thereon the usual transverse or rock shaft, which extends from the detecting to the replenishing side of the loom and is connected to the replenishing mechanism, as usual in this class of looms, and being well understood by those familiar with the art, its illustration and further description are not deemed necessary. Extending upwardly from the rock shaft is the arm 2 having pivoted thereto at 3, the latch 4, the rear end portion of which, as at 5, is adapted to be engaged at times by an operating member 6 which may be con- 100

nected to some going part of the loom, as for instance, the cam follower. Pivotsly mounted at 7 upon a bracket 8 rising from the loom frame is the transmitter 9, the end 5 portion 10 of which extends beneath the latch 4. The other end of the transmitter is turned laterally at 11 and provided with an incline 12. An arm or controller 13 is pivotsly mounted at 14 and extends over the 10 end 11 of the transmitter, the construction being such that when the arm or controller 13 is moved frontwardly, it will ride along the incline 12 and rock the transmitter to place the end 5 of the latch in the path of 15 movement of the operating member 6 to effect replenishment of filling.

The shipper stand 15 has extended therefrom the slotted bracket 16 to which is adjustably secured the bracket 17 which affords a proper support for the feeler stand, as will presently appear. The present invention has in view the provision of a feeler carrier for supporting the feelers and for coöperating with the stepped portion of a 25 bobbin within the shuttle when filling is substantially exhausted. There are two main types of feeler carriers known in the art, one a swinging feeler carrier mounted upon an arm pivoted to the loom frame, 30 and the other a reciprocating feeler carrier which is mounted for movement toward and from the front of the loom in a feeler stand. In the present instance the feeler carrier is shown as of the latter type.

35 Adjustably mounted upon the bracket 17 by means of the set screws 18, is the feeler stand 19 in which is mounted for reciprocating movement the feeler carrier 20. A spring 21 surrounds the frontwardly-projecting stem 22 of the feeler carrier, and normally holds the feeler carrier in its rearward feeling position, and returns it to such position after it has been displaced frontwardly. Extending from the feeler 40 stand 19 is the guide 23 under which projects the end of the transmitter 13, the construction being such that as the transmitter is moved frontwardly it will cause the latch 4 to be placed in the path of movement of the operating member.

45 Pivotsly mounted at 24 on the feeler carrier 20 is the actuator 25, the front end portion 26 of which is adapted to engage and move the end of the transmitter 13 frontwardly when, on a detecting beat, the end 26 of the actuator remains depressed in the present instance.

50 The present invention is especially applicable and advantageous in connection with 60 bobbins having stepped or ringed portions near the base thereof, such stepped or ringed portions being of gradually diminishing size from the base toward the tip of the bobbin. The rear end portion of the feeler carrier 65 20 is provided with stepped por-

tions 27, 28 and 29, three being indicated in the present drawings, but any number being within the contemplation of the invention. The stepped portions 27, 28 and 29 are adapted to coöperate with the steps 70 or rings 30 formed near the base portion of the bobbin and with which the stepped portions of the feeler carrier 20 contact when, on a detecting beat, filling is substantially exhausted.

75 Associated with each of the stepped portions at the rear end of the feeler carrier is a feeler, the end whereof is normally held rearwardly of the stepped portion with which it is associated, and is adapted to engage the filling on a detecting beat when a working supply is present in the shuttle. When, however, the supply of filling has reached the predetermined degree of exhaustion and a change of filling is desired, 80 the ends of the feelers remain in their normally projected position, at which time the stepped portion of the feeler carrier engages the stepped or ringed portion of the bobbin on a detecting beat, and advantage 85 is taken of the rearward position of all of the feeler members to initiate replenishment of filling.

90 In the present instance of the invention, the rear end portion of the feeler carrier 20 is provided with guideways 31 in each of which is mounted a feeler 32, one for each of the stepped portions of the feeler carrier. In the present instance, the feelers each consist of a rod slidingly mounted 100 upon the feeler and normally under the influence of a spring tending to move the feeler rearwardly into its projected position. As indicated in Figs. 3 and 4, each feeler is provided with a collar 33 against which rests 105 the base portion of a spring 34 seated in the guideway formed in the feeler, the construction being such that each of the feelers 32 will be held projected beyond the end of its associated stepped portion of the feeler carrier by the yielding influence of the spring 34. The guideways for the feelers 32 may be variously contrived in the feeler carrier, but in the present instance they are formed in the body of the feeler carrier at its rear 110 end portion, and a cover plate 35 serves to maintain the sliding feelers in their proper position on the feeler carrier.

115 Each of the feelers 32 is also provided with another portion 36, which extends forward from the body of the feeler and engages the rear downwardly-projecting portion of the actuator 25. The actuator 25 has connected to its downturned end portion 37 a plate 38 which may be adjustably held in 120 position by a set screw 39. The plate 38 is provided with suitable recesses 40 adapted to receive the forward push of the individual feelers when any of them is moved frontwardly relative to the feeler carrier 125 130

by the forward push upon it on a detecting beat. The construction is such that should any one of the feelers 32 be pushed forwardly relative to the feeler carrier on a detecting beat, its front end portion will engage the plate 38 and turn the actuator 25 into its inoperative position. Thus, the actuator 25 is under the individual control of each of the feelers and constitutes a common actuator for all of the feelers. If, however, on a detecting beat, all of the feelers remain in their rearwardly-projected position relative to the feeler carrier, then the actuator will remain in position to effect replenishment of filling as the feeler carrier moves forwardly.

The lay carries the usual shuttle box 41 for receiving the shuttle 42, and the front wall of the shuttle box and adjacent wall of the shuttle are each slotted as at 43 and 44 to permit the entrance of the end of the feeler carrier and several feelers on a detecting beat. The bobbin 45 has the usual holding rings 46 by which it may be held between the bobbin-holding jaws 47, and as hereinbefore stated, the portion of the bobbin adjacent the head thereof is provided with a series of rings or steps 30.

When a working supply of filling is present in the shuttle on a detecting beat, as indicated in Fig. 3, all of the feelers 32 will be moved forwardly relative to the feeler carrier, and will push against the downwardly-extending end 37 of the actuator and cause it to be placed in inoperative position relative to the transmitter, so that as the feeler carrier 20 is moved forwardly by the continued advance of the lay, replenishment will not be effected. As the filling approaches substantial exhaustion, the surface of the filling opposite the end of the feeler carrier and feelers will assume a substantially conical form corresponding to the conical tilt of the filling wind; and finally the filling will begin to be drawn from the stepped or ringed portions 30 as indicated in Fig. 4, until finally all of the feelers 32 will remain projected beyond the stepped portions of the filling carrier by entering the recess between the stepped rings of the bobbin, as indicated in Fig. 4, and the stepped portions 29 of the feeler carrier will engage the stepped portions or rings 30 of the bobbin, and force or push the feeler carrier forwardly, without, however, disturbing the relative position of the feeler carrier and feelers, so that the actuator will remain in position to effect replenishment of filling. Thus the feelers act individually and independently upon the actuator to prevent replenishment of filling when a working supply is still present opposite thereto on a detecting beat, and replenishment is only effected when all of the feelers remain projected beyond the stepped portions of the

feeler carrier on a detecting beat, a condition which indicates substantial exhaustion of filling, as indicated in Fig. 4.

What is claimed is:—

1. In a feeler mechanism for looms, the combination of a feeler carrier mounted for movement toward and from the front of the loom and having a stepped rear end for engaging stepped portions of a filling carrier or bobbin when the filling is substantially exhausted on a detecting beat, an actuator, a plurality of feelers each comprising a sliding rod having a portion extending rearwardly of one of the stepped portions of the feeler carrier and a second portion normally positioned to engage the actuator and to independently render it inoperative on a detecting beat until the filling is substantially exhausted, and springs acting on the several feelers to retain them in rearward position and permit the actuator to effect replenishment of filling when the filling is substantially exhausted opposite all the feelers on a detecting beat.

2. A feeler mechanism comprising, in combination, a feeler carrier having a stepped rear end for engaging stepped portions of a bobbin when the filling is substantially exhausted on a detecting beat, a feeler extending rearwardly of each of the stepped portions of the feeler carrier, an actuator adapted to be engaged and moved to an inoperative position by any one of the feelers when it is moved forwardly on the feeler carrier by the forward push of the filling on a detecting beat, and means for holding all the feelers in rearward position when the stepped portion of the feeler carrier engages the stepped portion of the bobbin on a detecting beat, and means controlled by the actuator for effecting replenishment of filling.

3. In a feeler mechanism for looms, the combination of a single actuator controlling a transfer mechanism, a plurality of individual feelers each of which comprises a sliding rod having a portion to engage the filling when a working supply is opposed to it on a detecting beat and a second portion normally positioned to engage the actuator and to independently render it inoperative as the feeler is pushed forwardly by the filling on a detecting beat, and yielding means acting to project the feelers rearwardly and permit the actuator to effect replenishment of filling only when all of the feelers remain in rearward position.

4. In a feeler mechanism for looms, the combination of a feeler carrier mounted for movement toward and from the front of the loom and having a stepped rear portion adapted to engage and to be moved forwardly by the filling on a detecting beat until substantial exhaustion thereof, and to then engage stepped portions of the bobbin,

a plurality of feelers, one feeler being associated with each stepped portion of the feeler carrier, and each being independently movable on the carrier, and an actuator which is rendered effective to replenish the filling when all of the feelers fail to be moved frontwardly by the stepped portions of the bobbin on a detecting beat.

5. In a feeler mechanism for looms, the combination of a feeler carrier, a series of feelers mounted to slide upon the feeler carrier and normally held in rearwardly projected position beyond the end of the feeler carrier, each of said feelers supported by 10 said carrier in position to feel for filling at a different point along the filling carrier, an actuator movable to and from an operative position on the feeler carrier and having a part adapted to be engaged by any one of 15 the feelers when it is pushed frontwardly relative to the feeler carrier on a detecting beat to inoperatively position the actuator and permit the actuator to be operatively positioned in case all the feelers remain in 20 their rearwardly projected position on a detecting beat.

6. In a feeler mechanism for looms, the combination of an actuator for effecting replenishment of filling, a plurality of individual feelers each comprising a sliding rod having a portion to engage the filling in the shuttle on a detecting beat and a second portion normally positioned to directly engage said actuator and to independently render 30 the actuator inoperative until the filling is substantially exhausted, each of said feelers supported in position to feel for filling at a different point along the filling carrier, and springs acting to maintain all the feelers in 35 rearward position when filling is substantially exhausted on a detecting beat to permit the actuator to effect replenishment of filling.

7. In a feeler mechanism for looms, the combination of a feeler carrier having a stepped rear end portion for engaging the stepped portion of a bobbin in the shuttle when the filling is substantially exhausted 45 on a detecting beat, and to be moved frontwardly thereby, an actuator mounted on the 50

feeler carrier for movement therewith and relative thereto, a plurality of feelers corresponding to the stepped portions of the feeler carrier each comprising a rod mounted for sliding movement on the feeler carrier and having a frontwardly extended portion adapted to engage the actuator when moved frontwardly relative to the feeler carrier, all of the said feelers being permitted to remain in their normal rearward position 55 relative to the feeler carrier when the filling is substantially exhausted and the stepped portion of the feeler carrier engages the stepped portion of the bobbin to effect replenishment of filling.

8. A feeler mechanism comprising a feeler carrier having a stepped rear end extending longitudinally of the shuttle to engage separate stepped rings on the bobbin when filling is substantially exhausted, an independent feeler extending through each of the stepped portions of the feeler carrier, each of said feelers supported by said carrier in position to enter a different recess between the stepped portions of the bobbin and feel 70 for the filling therein, and an actuator upon the carrier which is operatively positioned for effecting replenishment of filling only when all of the feelers remain in rearward position relative to the feeler carrier on a 75 detecting beat.

9. In a feeler mechanism for looms, the combination of a feeler carrier mounted for movement toward and from the front of the loom and having a rear engaging end adapted to receive the frontward pressure of a surface within the shuttle on a detecting beat and be moved frontwardly thereby, a plurality of feelers mounted on the feeler carrier for movement with and relatively thereto, a single actuator which is controlled by the plurality of feelers, each acting independently of the others, and means for replenishing filling only when all of the plurality of feelers detect substantial exhaustion of filling on a detecting beat.

In testimony whereof, I have signed my name to this specification.

MELVIN L. STONE.
